STUDY CARRELL

Clendon E. Crannell, 22 Washington Ave.,
Schenectady, N.Y. 12305

Filed Mar. 11, 1970, Ser. No. 21,848

Term of patent 14 years

Int. Cl. D6—04

U.S. Cl. D33—11

FIG. 1

FIG. 2

FIG. 3

FIG. 4

FIG. 1 is a front perspective view of a study carrell showing my new design.

FIG. 2 is an enlarged front elevational view thereof.

FIG. 3 is an enlarged side elevational view thereof.

FIG. 4 is an enlarged top plan view thereof.

I claim:

The ornamental design for a study carrell, as shown.
